UNITED STATES PATENT OFFICE.

LUCIAN ROSENWALD, OF KANSAS CITY, MISSOURI.

FOLDING BOX.

1,168,564.

Specification of Letters Patent. Patented Jan. 18, 1916.

Application filed July 24, 1914. Serial No. 852,920.

To all whom it may concern:

Be it known that I, LUCIAN ROSENWALD, a citizen of the United States, residing at Kansas City, in the county of Jackson and 5 State of Missouri, have invented a certain new and useful Improvement in Folding Boxes, of which the following is a specification.

My invention relates to improvements in 10 folding boxes.

It is particularly adapted for use in berry or fruit boxes.

The object of my invention is to provide a novel folding box which is cheap to construct, easily extended or collapsed, and which has great relative strength and durability.

The novel features of my invention are hereinafter fully described and claimed.

20 In the accompanying drawing which illustrates the preferred embodiment of my invention, Figure 1 is a perspective view of my improved box, shown extended and partly broken away. Fig. 2 is an enlarged vertical cross sectional view of the box, the U shaped brace being omitted. Fig. 3 is a reduced perspective view of the U shaped brace. Fig. 4 is an edge view of the box collapsed. Fig. 5 is a plan view of 25 the box collapsed. Fig. 6 is a plan view of the strip, which forms the sides of the box, stretched out. Fig. 7 is a plan view of the strip, which forms the bottom, stretched out. Fig. 8 is a top view of the box, reduced, the 30 removable bottom member being omitted. Fig. 9 is an enlarged vertical sectional view of the box, a lower part thereof, only, being shown, and the removable bottom member and the U shaped brace being shown in position.

Similar reference characters designate similar parts in the different views.

1 designates a rectangular strip which forms the sides of the box, the term "sides" 45 including the ends of the box. The strip 1 may be of any suitable material, such as sheet wood or card board. It is provided with a plurality of parallel flexible joints 2, which may be formed by creasing or scoring the strip. The strip 1 is bent at the creases, which are at right angles with the longitudinal edges of the strip, to form the shape of box desired, a rectangular box being shown, and the ends of the strip are secured together, as shown in Figs. 1, 2 and 8. 50 A second rectangular strip, having ap-

proximately the width of the length of the box inside, is provided with a middle rectangular portion 3, which forms the bottom of the box, and which at opposite edges is 60 connected by flexible parallel joints 4 with the lower ends respectively of two flaps 5, the upper ends of which are preferably respectively folded over the upper edges of opposite sides of the box and secured thereto 65 adjacent to said edges, as shown in Figs. 1, 2 and 8.

The bottom portion 3 is provided with a transverse flexible joint 6 which is in alignment with two vertical flexible joints 7 provided respectively in the two opposite sides 70 1 which are adjacent to the longitudinal edges of the strip forming the bottom. This disposition of the flexible joints 6 and 7 permits the box to be collapsed to the flat form 75 shown in Figs. 4 and 5. If desired, in collapsing the bottom portion 3 may be bent inwardly instead of outwardly along the joint 6.

The flaps 5 double two sides of the box, 80 thereby lending strength to the structure and making the box more durable and less liable to be distorted in use. Preferably, the bottom portion is disposed above the lower edges of the box, thereby leaving a 85 space for berries or fruit, when the boxes are piled one on top of the other.

For holding the sides and bottom securely extended, a removable bottom member 8 of substantially the inner dimensions of the 90 box, or a little less, may be mounted between the sides 1, and is adapted to rest upon the upper side of the bottom portion 3. The member 8 prevents the bottom portion bending upwardly along the joint 6. 95 If desired, additional means for holding the box extended may be provided in an inverted U shaped brace, the transverse portion 9 of which is disposed transversely to the joint 6 and is adapted to bear against 100 the under side of the bottom portion 3, so as to support the same and to prevent its bending downwardly along the joint 6. The said brace is provided at its ends with downwardly extending arms 10, each preferably 105 U shaped so as to be adapted to clamp the adjacent side 1 of the box, Fig. 9. After the box has been extended to the position shown in Fig. 2, the bottom member 8, when used, is placed therein upon the bottom portion 3. The brace is then applied, opposite sides of the box being slipped into the U 110

shaped arms 10, after which said arms may be fastened to the sides by indenting them with a suitable punch, not shown thereby forming indentations 11 in the arms and in 5 the sides of the box, the indentations interlocking with the ones adjacent thereto, thereby preventing the brace accidentally slipping from the box. The U shaped brace also serves to hold the lower edges of the 10 sides to which it is attached from being bent inwardly or outwardly.

In collapsing the box, the removable bottom member 8 is removed, after which the 15 arms 10 are sprung apart sufficiently to permit their removal from the sides engaged thereby. The brace may then be removed, after which the box may be collapsed by pressing the joint 6 downwardly or upwardly and pressing the sides of the box 20 toward each other.

I do not limit my invention to the structure shown and described, as modifications, within the scope of the appended claims, may be made without departing from the 25 spirit of my invention.

Having thus described my invention, what I claim and desire to secure by Letters Patent, is:—

1. A folding box comprising a plurality 30 of sides flexibly connected at the corners of the box, two opposite sides having each a vertical flexible joint intermediate of adjacent corners, two flaps secured respectively at their upper ends to opposite sides of the 35 box adjacent to the upper edges thereof, and having a bottom portion provided with a transverse flexible joint in alignment with said vertical joints, the bottom portion being disposed above the lower edges of the 40 box and flexibly connected at opposite edges with the lower ends respectively of said flaps, and an inverted U shaped member having its transverse portion disposed below said bottom portion, each of the arms 45 of the U shaped member being U shaped and adapted to clamp the adjacent side of the box.

2. A folding box comprising a plurality of sides flexibly connected at the corners of

the box, two opposite sides having each a 50 flexible vertical joint intermediate of adjacent corners of the box, and having a bottom portion flexibly connected at opposite edges with opposite sides of the box and disposed above the lower edges of the box 55 and provided with a flexible transverse joint in alignment with said vertical joints, and a U shaped member having its transverse portion disposed transversely to said transverse joint, each arm of the U shaped member 60 being U shaped and adapted to clamp the adjacent side of the box.

3. A folding box comprising a plurality of sides flexibly connected at the corners of the box, two opposite sides having each a 65 vertical flexible joint intermediate of adjacent corners of the box, and having a bottom portion flexibly connected at opposite edges with opposite sides of the box and disposed above the lower edges of the box 70 and provided with a flexible transverse joint in alignment with said vertical joints, and an inverted U shaped member having its transverse portion disposed transversely to 75 said transverse joint and adapted to support said bottom portion, the arms of said member each being U shaped and said arms being adapted to respectively clamp opposite sides of the box.

4. A folding box having a plurality of 80 sides flexibly connected at the corners, two opposite sides having each a central vertical flexible joint, the box having a bottom flexibly connected with the other two sides of the 85 box and having a flexible joint in alignment with said vertical joints, and an inverted U-shaped brace disposed below and adapted to support said bottom, the arms of said brace being U-shaped and adapted to clamp two opposite sides of the box.

In testimony whereof I have signed my name to this specification in presence of two subscribing witnesses.

LUCIAN ROSENWALD.
